UNITED STATES PATENT OFFICE.

CHARLES H. ROLLINS, OF WATERTOWN, MASSACHUSETTS, ASSIGNOR TO THE VENCLOS COMPANY, OF KITTERY, MAINE, A CORPORATION OF MAINE.

WATER-CLOSET BOWL.

No. 904,896.

Specification of Letters Patent.

Patented Nov. 24, 1908.

Application filed December 5, 1900. Serial No. 38,753.

To all whom it may concern:

Be it known that I, CHARLES H. ROLLINS, of Watertown, in the county of Middlesex and State of Massachusetts, have invented 5 certain new and useful Improvements in Water-Closet Bowls, of which the following is a specification.

This invention has relation to water-closet bowls, wherein provision is made for ventilation, the object of the invention being to provide a closet of the character referred to with a large unobstructed vent by which the air in the bowl may be carried to a convenient stack or conduit.

15 In many private residences, as well as large public buildings, it is the practice of sanitary engineers to carry the vent directly into a ventilating chamber or conduit communicating with the stack. In such cases, 20 however, if the closet trap becomes clogged, the contents of the bowl are liable to overflow through the vent into the vent conduit or chamber, with disastrous results. Consequently, the prime object of the present invention is to provide certain improvements 25 in the ventilating part of the closet, whereby the overflow, in case the outlet from the bowl becomes clogged, will be discharged over the flushing rim or top of the bowl and 30 not out through the vent.

Referring to the accompanying drawings, which illustrate one embodiment of my invention,—Figure 1 represents in perspective view a water-closet embodying my invention. Fig. 2 represents a side elevation of the same.

Referring to the drawings,—the bowl *a* is supported upon a base *b*, and is strengthened by a strut *a'*. The top of the bowl is formed 40 with the usual flushing rim, which extends rearwardly by the neck *c*². The neck *c*² is of sufficient length to project through the partition in front of which the closet is placed.

The flushing water is supplied to the neck 45 and flushing rim through a flushing pipe *d* leading from a convenient tank or other

source of supply, although in Fig. 2, the flushing pipe is shown as in the rear of the partition *m*.

The bowl, as shown, is of the wash-down 50 type, and it is provided with the waste-pipe *e* which with the bowl forms a trap *f*. The waste-pipe is shown as being formed with the bowl structure, but of course it may, if desired, be made of metal. In the rear portion of the bowl, below the flushing rim, and above the trap, there is a large unobstructed 55 opening which extends into an upwardly projecting neck *g*', the upper end of which is flush with the top of the flushing rim. To 60 this neck is attached a supplemental neck *h* which may be of metal or porcelain, or vitrified ware, as desired.

The supplemental neck and the neck *g*' are secured together in any desired way by 65 bolts, clamps, or otherwise, the two thus forming a vent which is of the same cross-sectional area throughout and which extend rearward and upward, and then rearward, terminating in a substantially horizontal 70 plane above the top of the flushing rim. By reason of this construction, the bowl may be set close to a wall or partition *m*, so that the neck may extend therethrough, and discharge 75 the air or odors into a vent chamber or conduit.

In case the trap should become clogged, the overflow of water from the bowl would not cause it to pass into the vent pipe, since the lowest portion of the end of the neck is 80 higher than the flushing rim of the bowl. It will be noticed that the vent and the mouth thereof are both unobstructed. The neck *c*² for the flushing water and the ventilating neck project rearward to the same extent, 85 and they together with the outlet of the bowl may project through the said partition *m*, so that no couplings are visible in front thereof.

Having thus explained the nature of the 90 invention, and described a way of constructing and using the same, although without at-

tempting to set forth all of the forms in which it may be made, or all of the modes of its use, I declare that what I claim is:—

A water-closet comprising a bowl, a flushing rim, an inlet neck communicating with the rim and projecting rearwardly from the bowl on one side thereof, an air-vent communicating directly with said bowl below said flushing rim, said vent terminating in a substantially horizontal neck above the plane

of the flushing rim, the two necks projecting rearwardly from the bowl and terminating in substantially the same vertical transverse plane, substantially as described.

In testimony whereof I have affixed my signature, in presence of two witnesses.

CHARLES H. ROLLINS.
